CART AND HOUSING COMBINATION FOR A PUMP APPARATUS

W. Don Seastrom, Los Angeles, Calif., assignor to Seastrom Manufacturing Co., Inc., Glendale, Calif.

Filed June 28, 1971, Ser. No. 157,790

Term of patent 14 years

Int. Cl. D15—02

U.S. Cl. D65—1 R

FIG. 1 is a front perspective view of my new design for a cart and housing combination for a pump apparatus;

FIG. 2 is a rear perspective view thereof;

FIG. 3 is a side elevational view thereof;

FIG. 4 is a rear elevational view thereof; and

FIG. 5 is a top plan view thereof.

I claim:

The ornamental design for a cart and housing combination for a pump apparatus, substantially as shown.
